CELIA M. BELANGER, OF NORTHAMPTON, MASSACHUSETTS.

EAR-PROTECTOR.

1,158,966.

Specification of Letters Patent.

Patented Nov. 2, 1915.

Application filed March 27, 1915. Serial No. 17,516.

To all whom it may concern:

Be it known that I, CELIA M. BELANGER, a citizen of the United States of America, residing at Northampton, in the county of 5 Hampshire and State of Massachusetts, have invented a new and useful Ear-Protector, of which the following is a specification.

My invention relates to improvements in head devices designed to prevent liquid 10 poured over or otherwise applied to the head from entering the ears, and consists of certain peculiar, curved, trough-like members, each being provided at one end with a cup, receptacle, or equivalent end-closing 15 or liquid-deflecting means, and a resilient support to which said members are attached, pivotal attachments being provided for said members when desired, and said support being made adjustable in the event such an 20 expedient be deemed advisable, all as hereinafter set forth.

In the process of shampooing the head, or of washing the hair, it is customary to place the subject in a reclining position, with the 25 head laid back in a suitably supported pan which catches the water or other liquid used in the operation, especially in the treatment of women or children who have long hair, and more or less of such water or other 30 liquid applied to the head and hair and rubbed into the scalp, by the operator, invariably runs down into the ears of the subject in the absence of some preventive or 35 protective means, thus causing discomfort and even pain in some cases, and the primary object of my invention is to provide a simple, convenient, comfortable, and entirely efficient device which is adapted to fit over and in front of the ears, and to receive 40 the liquid that would, in the absence of such device, be liable to run down into the same, and convey such liquid away from the entrances to the ears.

Other objects and advantages will appear 45 in the course of the following description.

I attain the objects and secure the advantages of my invention by the means illustrated in the accompanying drawings, in which—

50 Figure 1 is a perspective view of a protector which embodies a practical form of my invention, the same being disposed as it would actually appear if applied to the head and over the ears of a person arranged in 55 position for the treatment to which reference has been made; Fig. 2, a top plan of

one of the trough-like members, and, Fig. 3, a longitudinal vertical section through such member.

Similar numerals designate similar parts 60 through the several views.

The protector comprises a bowed or U-shaped support 1, and a pair of curved members 2, each of which is trough-like or V-shaped in cross section and provided at its 65 front end with a receiving, deflecting, or diverting member 2, such curved members being generally claw shaped or hook shaped and on that account hereinafter termed ear hooks. The ear hooks 2 are attached to the 70 free ends of the support 1.

The support 1 should be capable of holding the ear hooks 2 close to the sides of the head, and for that reason is preferably made of resilient material, such as wire or 75 flat spring steel.

Ordinarily the support 1, when made of resilient material, is capable of fitting heads of all sizes, but if a greater range of adjustment, than that naturally afforded by the 80 resilient nature of said support, be needed or desired, the same can be obtained by constructing the support in two parts and connecting such parts by means of a slip joint or equivalent medium. In the present case 85 the support 1 comprises two parts or sections, and these sections have overlapping terminals 4—4, to which are securely attached two bands 5, the arrangement being such that each of said terminals passes 90 through and can slide in the band on the other of said terminals. Some little frictional resistance is present in this construction, enough in fact to prevent the parts from slipping under ordinary conditions, 95 but not enough to prevent the terminals 4 from being slipped along on each other, when the necessary amount of force is properly applied; that is, applied to the sections at points just outside of the bands 5. The 100 size or capacity of the support 1 is increased by slipping the parts so as to shorten the terminals 4 and bring the bands 5 nearer together, and said capacity is decreased by slipping said parts so as to lengthen said 105 terminals and move said bands farther away from each other.

The better to adapt or fit the protector to different heads, I prefer to pivot the ear hooks 2 to the free terminals of the support 1, and to this end provide said hooks with lugs 6 and said support with bifur-

cated terminals 7 to receive said lugs, pivots 8 being passed through said parts 6 and 7. The ear hooks 2 are permitted to swing freely on the pivots 8, wherefore they may 5 be readily fitted to the sides of the head. Each lug 6 projects from the inner face of the back side of the ear hook 2 to which said lug is attached, at a point intermediate of the ends of said hook. The back side of each 10 ear hook 2 has a recess 9 therein, between the lug 6 on said side and the front end of said hook, to receive or accommodate the adjacent part of the support 1 and permit said hook to be swung outward at such end 15 without the upper edge of said side at any time contacting with said support.

Each ear hook 2 consists of a V-shaped trough-like structure, as already stated, which at the back end is bent or curved over 20 to form a prong 10. The prong 10 is the part of each hook 2 that fits over the top of the ear, to which said hook is applied, between the side of the head and the upper part of the rim of the ear, with the pointed 25 end of said prong behind said ear, while the rest of said hook lies against the corresponding side of the face in front of or above the entrance to said ear, when the head is laid back. The hooks 2 are, therefore, supported 30 partly by the ears and partly by the support 1, and the latter holds said hooks tightly against the sides of the head and face, so that no liquid can pass between. The V-shaped channel, indicated by the numeral 11 35 in Fig. 2, in each hook 2 extends the entire length of said hook, being open at both ends and on top. When the hooks 2 are in place the channels 11 therein receive the liquid that runs down the sides of the head in the 40 vicinity of the entrances to the ears, and such liquid passes away over the prongs 10 behind and out at the front ends of said channels, without any of the liquid being able to enter said ears. The hooks 2 form 45 shields for the ears and conduits for the liquid, so that the ears are protected completed, even the rims and lobes of the ears being kept dry, owing to the width and outward slant of the outer sides of said hooks, 50 and to the length of the hooks or of the parts thereof that are forward of the prongs 10.

Quite a stream of liquid is liable to flow 55 out of the front end of either hook 2, and, in order to divert such stream and cause it to pass at once into the aforesaid pan under the head, rather than permit it to run down onto the face and neck, I provide one of the cups 3 at said front end. In the construction, as illustrated in connection herewith, 60 the cups 3 are attached to the front ends of the inner sides of the ear hooks. The cups are arranged with their open ends at the back, when the ear hooks are in operative position, so that the liquid, that flows out of 65 the front ends of the channels 11 into said

cups, runs back out of the latter into the receptacle under the head, the liquid entering and leaving said cups through said open ends.

In practice, the support 1 is adjusted if necessary, and the hooks 2 are placed in position over and in front of the ears, as and in the manner hereinbefore fully explained, said support being permitted to rest at its bowed end either on or under the chin, as 75 desired. With the protector thus placed and while the head is inclined well back, the liquid is applied in the usual manner to the head and hair, and runs down the sides of the head, but is diverted from the ears and 80 caused to pass in front and back of them, by the hooks 2, so that none of the liquid gets into said ears. As previously observed, the liquid in the paths that lead to the ears is received in the channels 11, and escapes 85 therefrom at both ends, some of such liquid passing to the rear and down over the curved prongs 10 and out of said channels at or adjacent to the pointed ends of said prongs, and the rest of such liquid passing forward 90 into the cups 3 and then out of said cups again. Some of the liquid may, of course, escape from the front ends of the channels 11 without entering the cups 3 at all, but by far the larger percentage, if not all, of 95 the liquid enters the cups before making its final escape. The cups 3 or equivalent members would not be needed if the liquid would pass downward or fall directly upon leaving the front ends of the channels 11, but as 100 a rule there is so much impetus to the liquid that it would be projected a considerable distance beyond said front ends of the channels and without material change in direction, in the absence of said cups or members, 105 thereby wetting the person and clothing.

At the end of the shampooing or other operation, the hooks 2 are lifted or disengaged from the ears, and the protector is washed and cleansed and laid aside until 110 again required for use. It is very easy to wash, and disinfect if necessary, the protector, so that no difficulty is experienced in keeping the same clean and sanitary.

It will have been understood before this 115 that the ear hooks of these protectors, with the attached cups, are made in rights and lefts.

More or less change may be made in the shape, size, construction, and arrangement 120 of some or all of the parts of this device, without departing from the spirit of the invention.

What I claim as my invention, and desire to secure by Letters Patent, is—

1. As a new article of manufacture, an ear protector comprising a support, and a pair of longitudinally channeled ear hooks attached to said support.

2. As a new article of manufacture, an 130

ear protector comprising a support, and a pair of longitudinally channeled ear hooks attached to said support, said hooks being provided at their forward ends with means to divert liquid flowing out of such ends.

5. As a new article of manufacture, an ear protector comprising a support, and a pair of longitudinally channeled ear hooks attached to said support, said hooks being provided at their forward ends with cups having their front ends closed.

10. As a new article of manufacture, an ear protector comprising a resilient support, and a pair of longitudinally channeled ear hooks attached to the free ends of said support.

15. As a new article of manufacture, an ear protector comprising a support, and a pair of longitudinally channeled ear hooks movably attached to said support.

20. An ear hook, for an ear protector, consisting of a substantially V-shaped member, in cross section, terminating in the rear in a curved prong adapted to fit over the top 25 of the ear, between the side of the head and the upper part of the rim of said ear, said member opening upwardly and at the ends.

25. In an ear protector, an ear hook consisting of a substantially V-shaped member, in cross section, terminating at the rear in a curved prong adapted to fit over the top of the ear, between the side of the head and the upper part of the rim of said ear, said member opening upwardly and at the ends, 30 and an attachment at the front end of said member to divert the course of liquid flowing through the same.

35. In an ear protector, an ear hook consisting of a substantially V-shaped member, in cross section, terminating at the rear in a curved prong adapted to fit over the top 40

of the ear, between the side of the head and upper part of the rim of said ear, said member opening upwardly and at the ends, and a cup attached to the front end of said member and opening toward such end.

45. The combination, in an ear protector, with ear hooks consisting of substantially V-shaped members, in cross section, terminating at the rear in curved prongs adapted to fit over the tops of the ears, between the sides of the head and the upper parts of the rims of said ears, said members opening upwardly and at the ends, and means to direct downwardly liquid flowing from the front 50 ends of said members, of supporting means for said hooks, said supporting means being adapted to hold said hooks closely against the sides of said head.

55. The combination, in an ear protector, with ear hooks consisting of substantially V-shaped members, in cross section, terminating in the rear in curved prongs adapted to fit over the tops of ears, between the sides of the head and the upper parts of the rims 60 of said ears, said members opening upwardly and at the ends, and cups attached, with their closed ends forward, to the front ends of said members, of supporting means for said hooks, said supporting means being adapted to hold said hooks closely 65 against the sides of said head.

70. The combination, in an ear protector, with a substantially U-shaped support, of a pair of channeled ear hooks having flaring 75 sides, and provided with lugs, and pivotal means of connection between the free ends of said support and said lugs.
